[57] **CLAIM**

The ornamental design for a simulative toy box, substantially as shown and described.

DESCRIPTION

FIG. 1 is a perspective view of a simulative toy box showing my new design;

FIG. 2 is a front elevational view thereof;

FIG. 3 is a rear elevational view thereof;

FIG. 4 is a left side elevational view thereof, the side opposite being substantially a mirror image;

FIG. 5 is a top plan view thereof; and,

FIG. 6 is a bottom plan view thereof.

Fig. 1.

Fig. 2.

Fig. 3.
